UNITED STATES PATENT OFFICE

149,142

DESIGN FOR A FLUORESCENT DESK LAMP

Joseph F. Poor, Wenham, and Clement T. Baxter,
Beverly, Mass., assignors to Salem Manufacturing Company, Salem, Mass.

Application November 8, 1946, Serial No. 134,626

Term of patent 7 years

(CL. D48—20)

To all whom it may concern:

Be it known that we, Joseph F. Poor and Clement T. Baxter, citizens of the United States, residing at Wenham and Beverly, respectively, in the county of Essex and State of Massachusetts, have invented a new, original, and ornamental Design for Fluorescent Desk Lamp, of which the following is a specification, reference being had to the accompanying drawing, forming part thereof.

In the drawings:

Figure 1 is a perspective view of a fluorescent desk lamp showing our new design;
Figure 2 is a front elevational view; and
Figure 3 is an end elevational view.

We claim:

The ornamental design for a fluorescent desk lamp, as shown.

JOSEPH F. POOR.

CLEMENT T. BAXTER.
